UNITED STATES PATENT OFFICE.

FRANK L. GORMLEY, OF BROOKLINE, MASSACHUSETTS, ASSIGNOR TO A. O. NORTON, INC., OF ROXBURY, MASSACHUSETTS, A CORPORATION OF MAINE.

LIFTING-JACK.

1,276,902.

Specification of Letters Patent. Patented Aug. 27, 1918.

Application filed March 23, 1918. Serial No. 225,375.

To all whom it may concern:

Be it known that I, FRANK L. GORMLEY, a citizen of the United States of America, and a resident of Brookline, in the county 5 of Norfolk and Commonwealth of Massachusetts, have invented certain new and useful Improvements in Lifting-Jacks, of which the following is a specification.

This invention relates to lifting jacks, 10 and has for its object the provision of means for limiting the upward movement of the ram.

The invention consists in providing the base with a removable key normally ex- 15 tending into a slot in the ram, said slot having a closed lower end adapted to come into contact with said key when the ram has reached the upper limit of safety, thus preventing further elevation of the ram.

20 The invention further consists of means whereby the key may be removed from the slot in the ram when for any reason it is desired to remove the ram from the base.

The invention further consists in certain 25 novel features of construction and arrangement of parts, which will be readily understood by reference to the description of the drawings, and to the claims hereinafter given.

30 For the purpose of illustrating the invention one preferred form thereof is illustrated in the drawings, this form having been found to give satisfactory and reliable results, although it is to be understood that 35 the various instrumentalities of which the invention consists can be variously arranged and organized and the invention is not limited to the precise arrangement and organization of these instrumentalities as herein shown 40 and described, except as required by the scope of the appended claims.

Of the drawings:

Figure 1 represents an elevation of a jack embodying the principles of the present invention, the pawl carrying member being shown in section, and

45 Fig. 2 represents a vertical section of the same on line 2, 2, on Fig. 1.

Similar characters designate like parts 50 throughout the several figures of the drawings.

In the drawings, 10 represents a hollow base section provided at its top with a cylindrical extension 11 in which is mounted

the ram 12 provided with a female thread 55 13 adapted to be operated by the threaded male member 14 having secured to its lower end a bevel gear 15 adapted to mesh with a similar gear 16 keyed to a shaft 17 mounted in a suitable bearing in the plate 18 secured 60 by suitable studs 19 and nuts 20 to the base section 10. Secured to the outer end of the shaft 17 is the ratchet 21 with which engages a pawl 22 pivoted at 23 to the forked member 24 mounted upon the end of said 65 shaft 17 and held in position thereon by the cotter pin 25.

A handle 26 secured about the axis of the shaft 17 causes a rotation of the gears 16 and 15 and by means of the screw member 14 70 the raising of the ram 12. The ram 12 is provided with a groove 27 in which a member 28 secured to the cylindrical extension 11 cooperates to prevent the ram from turning within said cylinder during the raising 75 and lowering of the same.

The member 24 is provided with a spring-pressed bolt 29 which co-acts with the pawl 22 to cause its engagement with the ratchet 21 as desired. The lifting jack as described 80 is of well-known construction and embodies no features of the present invention. Heretofore in the use of jacks of this class, accidents are liable to occur on account of the operator continuing to raise the ram until 85 the screw thread 13 has become disengaged entirely from the male member or screw 14, much damage resulting from such carelessness both to the jack itself and to the article being lifted thereby. The aim of the present invention is to prevent such accidents and to avoid injury to the jack and the weight being lifted thereby. 90

This result is accomplished by making the slot 27 in the ram 12 with a closed lower end, having a shoulder 30 which will come into contact with the lower wall of the member or key 28 when the ram has reached its upward limit of safety.

It is obvious that when the shoulder 30 100 is brought into contact with the key 28 further upward movement of the ram 12 will be effectually prevented.

At times it is desired to remove the ram 12 from the cylinder 11 either for the purpose of repairing the jack or for some other cause.

In order to effect the removal of the ram

12 the key 28 is made so that it may be quickly removed from the path of the shoulder 30.

This key 28 extends through a slot 31 in 5 the cylinder 11 and a portion of said key 28 extends outwardly from the cylinder 11 between two vertical ears 32, having a pin 33 therein extending through an inclined slot 34 in said key 28.

10 Beneath the key 28 and between the ears 32 is positioned a cam member 35 pivotally mounted on a pin 36 secured in the ears 32. When the cam member 35 is in the position shown in Fig. 2 the key 28 will be locked in 15 elevated position with its upper wall abutting the wall 37 at the upper end of the slot 31 and with its inner end projecting into the slot 27.

The cam member 35 is provided with a 20 ring 38, or some similar member by which the said cam member may be pulled out from beneath the key 28, thereby permitting said key 28 to drop downwardly, and at the same time on account of the inclination 25 of the slot 34 said key 28 will be moved outwardly.

When in this lowest position the inner 30 end of the key 28 will be out of the path of the shoulder 30 and the ram 12 may be removed.

When the ram 12 has been replaced the 35 key 28 is raised to its normal elevated position and the cam member 35 is forced beneath it, thereby effectually locking it in operative position.

It will be noted that in this construction of safety device for lifting jacks all the parts thereof are permanently attached to the jack and cannot be misplaced.

40 If the key 28 becomes worn or broken, said key may be removed by first forcing the pin 33 from the ears 32 in which its ends are positioned.

A new key may then be positioned in the 45 slot 31, and the pin 33 inserted in the ears 32 and through the inclined slot 34 and the jack will again be ready for use.

In like manner the pin 36 may be forced from its bearings in the ears 32 if it is desired to replace the cam member 35.

It is believed that the operation and many advantages of the invention will be thoroughly understood without further description.

55 Having thus described my invention, I claim—

1. In a lifting jack, the combination of a cylinder, a ram therein provided with a vertical peripheral slot with a closed lower end; 60 a key mounted in a slot in said cylinder with its inner end normally extending into said peripheral slot; and a movable member for locking said key in its normal position, but adapted to be removed from the path of said

key thereby permitting said key to be moved 65 outwardly from said slot.

2. In a lifting jack, the combination of a cylinder, having parallel vertical ears extending therefrom; a ram in said cylinder having a vertical peripheral slot with a closed lower end; a key interposed between said ears and normally extending through said cylinder into said slot; and means for locking said key in its inner normal position and adapted to be removed from the path of 75 said key thereby permitting said key to be moved outwardly from said slot.

3. In a lifting jack, the combination of a cylinder having parallel ears extending therefrom; a ram in said cylinder having a vertical peripheral slot with a closed lower end; a key interposed between said ears and extending through said cylinder into said slot, said key having an inclined slot extending therethrough; a pin mounted in said 85 ears and extending through said slot; and means for normally retaining said key in operative position.

4. In a lifting jack, the combination of a cylinder, having parallel ears extending 90 therefrom; a ram in said cylinder having a vertical peripheral slot with a closed lower end; a key interposed between said ears and extending through said cylinder into said slot, said key having an inclined slot extending 95 therethrough; a pin mounted in said ears and extending through said slot; and means acting on the lower end of said key for normally retaining said key in operative position.

5. In a lifting jack, the combination of a cylinder, having parallel ears extending therefrom; a ram in said cylinder having a vertical peripheral slot with a closed lower end; a key interposed between said ears and extending through said cylinder into said slot, said key having an inclined slot extending therethrough; a pin mounted in said ears and extending through said slot; and means pivoted to an ear and acting on the 110 lower end of said key for normally retaining said key in operative position.

6. In a lifting jack, the combination of a cylinder, having parallel ears extending therefrom; a ram in said cylinder having a vertical peripheral slot with a closed lower end; a key interposed between said ears and extending through said cylinder into said slot, said key having an inclined slot extending therethrough; a pin mounted in said 120 ears and extending through said slot; and a cam member pivotally mounted between said ears and adapted to retain said key in operative position.

7. In a lifting jack, the combination of a 125 cylinder, having parallel ears extending therefrom; a ram in said cylinder having a vertical peripheral slot with a closed lower

end; a key interposed between said ears and extending through said cylinder into said slot, said key having an inclined slot extending therethrough; a pin mounted in said ears and extending through said slot; a cam member pivotally mounted between said ears and adapted to retain said key in operative position; and means whereby said cam member may be removed from beneath said key.

10 8. In a lifting jack, the combination of a cylinder having a slot therethrough with its upper wall perpendicular to the axis of said cylinder; a ram having a barrel portion in said cylinder, said barrel portion being of equal diameter throughout its length and

having a vertical peripheral slot closed at the lower end; a rectangular key in said cylinder slot; means for positively locking said key in said slot with its upper edge abutting the upper wall of the cylinder slot and 20 adapted to be actuated to permit said key to be moved outwardly free from the slot in said ram.

Signed by me at 4 Post Office Square, Boston, Mass., this 21st day of March, 1918. 25

FRANK L. GORMLEY.
